UNITED STATES PATENT OFFICE.

JAMES P. RATIGAN, OF COALINGA, CALIFORNIA.

COMBINED PIPE AND ROD WRENCH AND CUTTER.

1,178,347.

Specification of Letters Patent.

Patented Apr. 4, 1916.

Application filed December 20, 1915. Serial No. 67,811.

To all whom it may concern:

Be it known that I, JAMES P. RATIGAN, a citizen of the United States, residing at Coalinga, in the county of Fresno and State of California, have invented certain new and useful Improvements in Combined Pipe and Rod Wrenches and Cutters; and I do declare the following to be a full, clear, and exact description of the invention, such as will enable others skilled in the art to which it appertains to make and use the same.

This invention relates to improvements in combined pipe and rod wrenches and cutters.

15 One object of the invention is to provide a tool for more firmly and securely clamping or gripping a rod or pipe than heretofore and without injury to such pipe or rod.

Another object of the invention is to provide a tool having a movable block or jaw provided with a plurality of sides, each of which may be brought into engagement with the rod, pipe or other object intended to be clamped, cut or otherwise operated upon.

25 A still further object resides in the provision of a device which will be simple, strong, durable and inexpensive in construction, efficient and reliable in operation, and well adapted to the purpose for which it is designed.

With these and other objects in view the invention consists of certain novel features of construction and the combination and arrangement of parts as will be hereinafter 35 fully described and claimed.

In the accompanying drawings in which similar reference numerals indicate like parts throughout the several views, Figure 1 is a side elevation of a device constructed 40 in accordance with this invention, showing a rod clamped between the jaws thereof; Fig. 2 is a front elevation of the same; and Fig. 3 is a side elevation of the device showing the manner in which it is used when 45 cutting a rod or pipe.

In these drawings, constituting a part of this application, 1 represents a metal casting having a notch 2 in its front edge, thereby forming a substantially U-shaped head. One arm 3 of this head 1 is provided 50 with a threaded aperture 4, while the other arm 5 is provided on its inner face with a transversely extending groove 6. The edge of the portion of the head 1 between the arms 3 and 5 thereof is substantially flat, for a purpose hereinafter to be described.

Pivoted at one end to one side of the head 1 in any suitable manner, preferably by a bolt 7, is a link 8, the other end of which is provided with an elongated aperture 9. 60 Sliding between the arms 3 and 5 of the head 1 and in the notch 2 is a substantially rectangular block 10 having the work engaging elements to be hereinafter described. This block 10 is pivoted to the last mentioned end of the link 8 by a bolt 11, the shank portion of which extends through the aforesaid elongated aperture 9 and into said block. Thus it may be seen that when the block 10 is moved to its uppermost and lowest 70 positions it will not bind as otherwise it would do.

The block 10 is provided with substantially flat edges, one of which is provided with a transversely extending groove 12 75 while the adjacent edge thereof is provided with a recess 13 adjacent to the opposite side edges of which are alined bearings 14. Revolubly mounted in these bearings 14 is the shaft 15 of a rotary disk cutter 16. By 80 having the block 10 loosely and pivotally connected to the link 8 as hereinbefore described, it may be seen that said block may be turned to bring either the edge in which the groove is disposed opposite the inner face 85 of the arm 5, or the edge whereon the cutter is mounted opposite such face. The substantially flat edges of the block slidably engage the beforementioned flat portion of the head between the arms thereof, and prevent 90 the block from becoming angularly disposed.

Operating within the threaded aperture 4 in the arm 3 of the head 1 is a screw 17, the upper end of which is provided with a suitable handle 18. However, this handle 18 95 may be dispensed with and the upper end of the screw 17 may be squared as shown at 19 in Fig. 3 of the drawings for engagement with a suitable wrench. The lower end of the screw 17 extends into the notch 2 and 100 bears against the upper edge of the block 10, whereby when the former is turned the latter is moved downwardly.

In Fig. 1 of the drawings a rod R is shown clamped between the block 1 and the 105 arm 5, the opposite sides of said rod R being received in the grooves 12 and 6 respectively whereby it may be seen that the rod is in no way injured. This makes the device particularly adapted for clamping or gripping the polish rods of oil wells, for, without 110 going into any details of the reasons why

it is desired to grip such rods, it is to be understood that no injury must be done to them and at the same time powerful clamping force must be exerted upon them.

5 In Fig. 3 of the drawings the block 10 is shown with the cutter 16 in position for cutting the rod R, and while in this position either the rod is revolved or the head 1 is turned around said rod. The depth of the 10 cut may be regulated by turning the screw 17, as will be readily understood.

From the foregoing it may be seen that the 15 objects of the invention have been effectively carried out. However, it is to be understood that various minor changes in form and proportion may be resorted to without departing from the spirit of this invention, and hence I do not wish to limit myself to the structure herein shown and described 20 other than that set forth in the appended claims.

I claim:—

1. A device of the character described comprising a U-shaped head having a 25 threaded aperture in one arm thereof, the edge of the portion of said head between the arms thereof being substantially flat, a rectangular block slidable between the arms of said head and having substantially flat edges 30 adapted to be brought into slidable engagement with the aforesaid flat edge of said

head, a link pivoted at one end to one side of said head and loosely pivoted at its other end to said block, and a screw operating in said aperture and having its inner end in engagement with said block for moving the latter. 35

2. A device of the character described comprising a U-shaped head having a threaded aperture in one arm thereof, the 40 edge of the portion of said head between the arms thereof being substantially flat, a rectangular block slidable between the arms of said head and having substantially flat edges adapted to be brought into slidable engagement with the aforesaid flat edge of said head, a link pivoted at one end to one side of said head and loosely pivoted at its other end to said block, work engaging elements arranged on two edges of said block, 45 adapted to be brought opposite the inner ends of the other arm of said head, and a screw operating in said aperture and having its inner end in engagement with said block for moving the latter. 50

In testimony whereof I have hereunto set my hand in presence of two subscribing witnesses.

JAMES P. RATIGAN.
